UNITED STATES PATENT OFFICE.

DANIEL B. HILL, OF GRAYVILLE, ILLINOIS.

ACETYLENE-GAS GENERATOR.

1,191,786.

Specification of Letters Patent. Patented July 18, 1916.

Application filed May 18, 1915. Serial No. 28,904.

To all whom it may concern:

Be it known that I, DANIEL B. HILL, a citizen of the United States, residing at Grayville, in the county of White and State 5 of Illinois, have invented certain new and useful Improvements in Acetylene-Gas Generators; and I do hereby declare the following to be a full, clear, and exact description of the invention, such as will enable others skilled in the art to which it 10 appertains to make and use the same.

This invention is an improved acetylene gas generator, the object of the invention being to provide an improved gas generator 15 of this class which operates to automatically feed carbid to the generating vessel as the same is wanted and which is also provided with automatically operating means for supplying the feed hopper with carbid.

20 The invention consists in the construction, combination and arrangement of devices hereinafter described and claimed.

In the accompanying drawings:—Figure 1 is a vertical central sectional view of an 25 acetylene gas generator constructed in accordance with my invention and showing the gas bell in raised position and the feed valve closed. Fig. 2 is a detail horizontal sectional view on the plane indicated by the 30 line 2—2 of Fig. 1, the cross bar being omitted. Fig. 3 is a similar view on the plane indicated by the line 3—3 of Fig. 1. Fig. 4 is a detail plan of the fixed valve disk. Fig. 5 is a detail horizontal sectional view 35 on the plane indicated by the line 5—5 of Fig. 1, looking in the direction indicated by the arrow.

The tank 1, which forms a generating chamber, has a gas feed pipe or surface 40 pipe 2 leading therefrom and the tank is provided with a removable cover 3 which may be secured in place by any suitable means. An annular wall 4 is on the inner side of the tank 1, spaced therefrom, and 45 arranged at a suitable distance from the upper end of said tank, said annular wall and the wall of the tank forming a sealing chamber 5. A gas bell 6 is arranged in the upper portion of the tank and is sealed in the 50 water in the sealing chamber. A feed hopper 7 is arranged within the wall 4 and is provided at its center with a downwardly extending spout or discharge neck 8 in which is a fixed valve disk 9 which is provided with feed openings 10.

A tubular standard 11 rises from and is

secured to the fixed valve disk 9 and is provided at its upper end with a covered fixed cylindrical casing 12 in the top of the tank, and which has a noncircular opening 13 in 60 the cover. A cross bar 14 is arranged in the casing at a suitable distance from its upper end. A shaft 15 extends through the tubular standard, has its lower end stepped on a bearing 16 which is supported at the 65 lower end of the spout 8, and said shaft is also provided at its lower end with a valve disk 17 secured thereto and adapted to turn therewith, said disk being provided with openings 18 which may be moved into or out 70 of registry with the openings 10 of the fixed disk 9. At the upper end of the shaft is a hollow cylindrical drum 19 the wall of which is provided, in opposite sides, with cam slots 20.

75 A non-circular operating shaft 21 of same cross section as the opening 13 is guided for vertical movement in and through the opening 13, has a head 22 at its upper end and is provided at its lower end 80 with a disk 23, and said disk having cam studs 24 projecting radially therefrom and engaged in the cam slots 20. A coiled spring 25 is arranged around the shaft 21, its lower end bearing on the cross bar 14 and 85 its upper end engaging a stop device 26 with which the shaft 21 is provided. Said spring serves to normally move the shaft 21 together with its disk 23 upwardly and to keep the cam studs 24 in the upper end 90 of the cam slots 20 and normally hold the valve disk 17 with its openings 18 out of registry with the openings 10 of the disk 9 and thereby normally cut off the supply of carbid from the hopper to the generating 95 chamber.

In the operation of my improved acetylene gas generator, when the gas bell descends owing to the consumption of gas from the generator, the top of the bell bears 100 on the upper end of the shaft 21 so that said shaft moves downwardly, against the tension of its spring 25, with the bell thus causing the cam studs 24 which move downwardly in right lines, by engagement with the diagonal cam slots 20 to partly turn the drum 19 and hence also the shaft 15 and valve disk 17 so that the openings 18 of said valve disk are caused to register with the openings 10 of the disk 9 and hence carbid is supplied from the hopper to the generating tank or chamber. As the gas pres-

sure increases the bell rises, permitting the shaft 21 to be moved upwardly by the spring 25 and hence causing the valve disk 17 to be partly reversely turned and cut off 5 the supply of carbid to the generator.

To automatically supply the hopper with carbid when the main supply is exhausted and hence enable the apparatus to continue automatically in operation for a considerable period of time I provide a reservoir 10 chamber 27 which is here shown as arranged in one side of the hopper, which is adapted to contain a supply of carbid and is provided with a vertically movable gate, door 15 or valve 28 in one side. A bent lever 29 is pivotally mounted on the reservoir chamber as at 30 and has its longitudinal arm 31 connected by a suitable chain 32 to the gate or valve 28 and has its vertical arm 33 provided at its upper end with a head 34. This head is at a lower level than the lower limit of the head 22. Ordinarily the bell does not descend so low as to strike the head 34. When, however, the carbid in the hopper 20 has been all exhausted, and the bell is in its lowest position, the top wall of the bell is about one-eighth of an inch above the head 34 of the arm 33. When the bell is in this position, and by removing the cover 25 3, a downward pressure may be applied to the bell at a point directly above the head 34. This pressure will tilt the bell and cause its top wall to engage and move the head 34 downwardly, resulting in the opening 30 of the valve 28. As soon as the valve 28 is opened, the carbid in the chamber 27 will fall into the hopper 7. After the pressure has been removed therefrom, the bell will return to its normal position, and the 35 valve 28 will close. As the bell is still in its lowest position, and the openings 10 in registration with the openings 18, a charge 40 of carbid will be fed from the hopper 7 to the generating tank or chamber.

Having thus described my invention, I 45 claim:—

1. In an acetylene gas generator, a generating tank, a carbid feed hopper having a downwardly extending discharge spout, a 50 fixed valve disk having openings and ar-

ranged in said spout, a valve disk pivotally mounted in said spout under said fixed disk and having openings movable into and out of registry with those of the fixed disk, a shaft rising from the center of said pivotally mounted valve disk, a drum at the upper end of said shaft and having a cam slot, a tubular standard rising from and secured to the fixed disk and provided at its upper end with a fixed casing in which said drum is rotatably arranged, a vertically movable shaft arranged in said casing extending above the upper end thereof and having a cam stud engaging said cam slot of the drum, means to prevent the rotation 60 of said vertically movable shaft, a gas bell to depress said shaft when the bell lowers and thereby turn the drum and movable valve disk and cause the openings of the latter to register with those of the fixed valve 65 disk and a spring to move said vertically movable shaft upwardly when the bell rises.

2. In an acetylene gas generator, a generating tank, a carbid feed hopper having a discharge spout, a fixed valve disk having 70 openings and arranged in said spout, a valve disk rotatably mounted in said spout and having openings movable into and out of registration with the openings of the fixed disk, a shaft rising from the center of said 75 rotatably mounted valve disk, a drum at the upper end of said shaft and having a cam slot, a shaft adapted to be moved vertically with relation to said drum and having a cam stud engaging said cam slot, means to prevent the rotation of said vertically movable shaft, a gas bell adapted to engage and move said shaft downwardly with relation to said drum when the gas pressure in the generating tank falls below a predetermined 80 degree, and a spring engaging said shaft and adapted to move it upwardly with relation to said drum when the gas pressure in the generating tank elevates the bell.

In testimony whereof I affix my signature 85 in presence of two witnesses.

DANIEL B. HILL.
